UNITED STATES PATENT OFFICE.

LEO HERMAN ALTGILBERS, OF FORT DODGE, IOWA.

STREET OR ROAD SNOWPLOW.

Application filed January 18, 1927. Serial No. 161,777.

The principal object of my invention is to provide a simple and economical means for removing snow from streets, highways and the like. 5 A further object is to provide a snow plow which will deposit the snow at the side of the street or highway. More specifically, the object of my invention is to provide a device for the removal 10 of snow from roads or highways which shall embody therein, as a co-acting part, an automotive road vehicle which shall be of such construction that the component parts shall be readily separable to permit use of the 15 vehicle for any purpose that is desired and to enable conversion quickly and easily even by unskilled workmen of the vehicle, into a snow plow when desired. More specifically, the object of my invention 20 is to detachably mount a snow plow on the front end of an automobile, said snow plow having centrifugal fans in operative engagement with the crank shaft of the internal combustion motor of the automobile. 25 A still further object is to so construct my device that it may be secured to the front axle of an automobile whereby the snow plow will be guided by the steering wheel of the automobile. 30 A further object is to so construct the plow that snow, not being handled by the centrifugal fans will be forced to the side of the road independent of the fans, and also to so construct the plow that all snow entering 35 the path of the fans will be in broken and loose condition. These and other objects will be apparent to those skilled in the art. 40 My invention consists in the construction, arrangement and combination of the various parts of the device, whereby the objects contemplated are attained as hereinafter more fully set forth, pointed out in my claims and illustrated in the accompanying drawings, 45 in which: Figure 1 is a top plan view of my snow plow mounted on an automobile and ready for use. 50 Figure 2 is a side elevation of my complete device installed on an automobile. Figure 3 is a rear sectional view of my snow plow taken on line 3-3 of Figure 2. A section of the device is cut away to more 55 successfully illustrate the mechanism for driving the two centrifugal fans. I have designated the ordinary automo-

bile by the numeral 10. I have used the numerals 11 and 12 to designate the frame of my snow plow. The members 11 and 12 are pivotally secured to the members 13 and 14 respectively, which are designed to be secured to the front axle 15 of the automobile by U bolts 16. The forward ends of the members 11 and 12 extend downwardly and outwardly and terminate a slight distance 60 above the roadway. Secured to these members is my two-way snow plow or shovel 17. The numerals 18 and 19 designate braces for more securely holding the plow or shovel 17 in proper position. On each side of the center line of the shovel 17 is an opening 20 and 21, back of each is a centrifugal fan housing 22 and 23. Each of the fan housings 22 and 23 have an outlet pipe 24 and 25 extending upwardly. Rotatably mounted 65 upon each of these outlet pipes 24 and 25 and communicating with each respectively is a distributing pipe 26 and 27 of L construction. Thus it will readily be seen that by turning the distributing pipes, the snow 70 passing therefrom, may be deposited in any desired location relative to the travel of the automobile. Rotatably mounted in each of the centrifugal fan housings in a centrifugal fan 28 and 29. The numeral 30 designates 75 a gear housing position directly back of the two fan housings. Rotatably mounted in the two bearing members 31 and 32 secured to the housing 30, is a shaft 33. Secured to one end of the shaft 33 against relative rotation is a bevel gear 34 in operative engagement with the bevel gear 35 which is permanently secured to the centrifugal fan shaft 36 of the centrifugal fan 28. Secured to the opposite end of the shaft 33 against 80 relative rotation is the bevel gear 37 in operative engagement with the bevel gear 38 which is permanently secured to the centrifugal fan shaft 39 of the centrifugal fan 29. It will readily be seen by those skilled in the 85 art that if the shaft 33 is rotated, the two centrifugal fans will also be rotated in their respective housings and that if snow entered the openings 20 and 21 it would be forced out of the distributing pipes 26 and 27. I 90 have used the numeral 40 to designate a sleeve member capable of embracing the crank shaft 41 of the internal combustion engine and having notches 42 capable of engaging the crank shaft pin 43. Secured to 95 this sleeve 40 is the drive shaft 44 rotatably mounted on a bearing member 45 which is

supported by the hand crank guide case 46 of the automobile. Secured to the forward end of this shaft 44 is a universal joint 47. The drive shaft 48 leading from this joint is square at its forward end and enters and is capable of sliding movement in a square hole in the hollow drive shaft 49 which is secured at its opposite end to the universal joint 50. The numeral 51 designates a fourth drive shaft leading from the universal joint 50, journaled near its forward end in the bearing members 52 and 52' and extending within the housing 30. Permanent secured to the free end of this shaft 51 is the bevel gear 53 in operative engagement with the bevel gear 54 permanently secured to the shaft 53. By this arrangement when the internal combustion motor is running, both of the centrifugal fans will be rotating at a speed relative to the speed of the motor. This is very advantageous due to the fact that when the snow is very bad and a great amount of it is to be handled, the car must travel in either low or intermediate gear and the centrifugal fans will thereby be rotating very fast and will be able to take care of the greater amount of snow. By the frame of the plow being pivotally mounted to the front axle the variations of the road bed are compensated for. It is because of this construction that it is necessary for the shafts 48 and 49 to slide one within the other. The universal joints 47 and 50 also help compensate further changing of the position of the snow plow relative to that of the automobile.

The practical operation of the device is as follows: Secure the members 13 and 14 to the axle 15 by the U bolts 16. Force the sleeve 40 onto the crank shaft 41 in order that the notches 42 therein will engage the pin 43. This sleeve 40 is yieldingly held on the crank shaft 41 by the spring 55. The complete device is now ready for use. It is merely necessary to remove the U bolts 16 and the plow will be disconnected from the automobile which may then be used for any other purpose desired.

In order that snow, striking the plow when the car is going at considerable speed, will not be thrown over the driver of the automobile, an outwardly and forwardly extending flange 56 is provided on the top margin edge of the two-way snow plow or shovel 17. The numeral 57 designates a brace for holding the complete device more rigid and also supports the bearing member 52'. I have used the numeral 58 to designate two caster wheels secured to the braces 11 and 12 for supporting the plow a slight distance from the roadway. By using a two-way plow, snow failing to enter the openings 20 and 21, will be thrown to the

side of the road. This construction also aids in breaking up snow that has hardened or crusted at the surface so that the fans will handle it more rapidly and without damage to the same.

It will readily be appreciated that my apparatus is simple in construction and operation and is of durable construction and is of such character as will admit of operation by any person capable of driving a motor vehicle.

It is apparent that some changes may be made in construction and arrangement of my device without departing from the real spirit and purpose of my invention, and it is my intention to cover by my claims any modified forms of structure or use of mechanical equivalents which may be reasonably included within their scope.

I claim:

1. In combination with an automobile, a snow plow comprising a frame pivotally secured to the front axle of the automobile, a snow plow mounted on said frame and having a centrifugal fan, wheels for supporting the front end of said plow a certain distance from the roadway, a sleeve having a notch designed to embrace the end of the crank shaft of the motor of the automobile originally intended for the hand crank and engaging the catch pin in the crank shaft, a drive shaft secured at one end to said sleeve, a second shaft connected to the opposite end of said first mentioned drive shaft and having its free end squared, a third drive shaft having a square opening designed to embrace the free end of the second mentioned drive shaft and capable of sliding movement thereon, and a fourth drive shaft operatively connected to said third drive shaft and said centrifugal fan.

2. In combination with an automobile, a snow plow comprising a frame secured to the front axle of the automobile, a snow plow mounted on said frame, a centrifugal fan secured to said plow portion, a sleeve having a notch designed to embrace the end of the crank shaft of the motor of the automobile originally intended for the hand crank and engaging the catch pin in the crank shaft, a bearing member loosely mounted in the hand-crank guide case, a shaft rotatably mounted in said bearing member and secured at one end to said sleeve, a second drive shaft, a universal joint for connecting the two mentioned shafts, a means for operatively connecting the second mentioned drive shaft with the centrifugal fan, and a means for yieldingly holding the said sleeve on the said crank shaft.

LEO HERMAN ALTGILBERS.
